CLAIM

The ornamental design for a baseball related container, as shown and described.

DESCRIPTION

FIG. 1 is a perspective view of a baseball related container; FIG. 2 is a right side elevational view thereof; FIG. 3 is a left side elevational view thereof; FIG. 4 is a front elevational view thereof; FIG. 5 is a rear elevational view thereof; FIG. 6 is a top plan view thereof; and, FIG. 7 is a bottom plan view thereof. The dash-dash broken lines shown in the drawings illustrate portions of the baseball related container that form no part of the claimed design.
